Primary Examiner — Kevin K Rudzinski*Assistant Examiner* — Richard Kearney(74) *Attorney, Agent, or Firm* — Jeffrey T. Stover; Haynsworth Sinkler Boyd, P.A.(57) **CLAIM**

The ornamental design for a lighting fixture, as shown and described.

DESCRIPTION

FIG. 1 is a bottom perspective view of a lighting fixture showing our new design;

FIG. 2 is a top perspective view thereof;

FIG. 3 is a left elevation view thereof.

FIG. 4 is a right elevational view thereof;

FIG. 5 is a front elevation view thereof;

FIG. 6 is a back elevation view thereof;

FIG. 7 is a top plan view thereof; and,

FIG. 8 is a bottom plan view thereof.

The broken line disclosure in the views represents environmental structure which forms no part of the claimed design.
